Primary Examiner — Darcey E Gottschalk*Assistant Examiner* — Vanessa M. Pursley(74) *Attorney, Agent, or Firm* — Alexandra S. Anoff(57) **CLAIM**

The ornamental design for a primary package for a solid, single dose beauty care composition, as shown and described.

DESCRIPTION

FIG. 1 is a first perspective view of a primary package for a solid, single dose beauty care composition, embodying our new design;

FIG. 2 is a second perspective view of the primary package of FIG. 1;

FIG. 3 is a front view of the primary package of FIG. 1;
FIG. 4 is a back view of the primary package of FIG. 1;
FIG. 5 is a first side view of the primary package of FIG. 1;
FIG. 6 is a second side view of the primary package of FIG. 1;

FIG. 7 is a third side view of the primary package of FIG. 1; and,

FIG. 8 is a fourth side view of the primary package of FIG. 1.

In the drawings, the broken lines show portions of a primary package for a solid, single dose beauty care composition that form no part of the claim.
